(57) **CLAIM**

We claim the ornamental design for a rack mountable load carrier, as shown and described.

DESCRIPTION

FIG. 1 is a perspective view of a rack mountable load carrier in a closed configuration;

FIG. 2 is an alternate perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and

FIG. 8 is a bottom plan view thereof;

FIG. 9 is a perspective view of a rack mountable load carrier in an open configuration;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof; and,

FIG. 15 is a bottom plan view thereof.

Broken lines illustrate unclaimed portions of the rack mountable load carrier; broken lines form no part of the claimed design.
